FREDERICK WATERS,

By

Louis H. Schmidt

Attorney

UNITED STATES PATENT OFFICE.

FREDERICK WATERS, OF LYONS FALLS, NEW YORK.

RATCHET WRENCH.

Application filed July 31, 1924. Serial No. 729,324.

To all whom it may concern:

Be it known that I, FREDERICK WATERS, residing at Lyons Falls, county of Lewis, State of New York, a citizen of the United States, have invented certain new and useful Improvements in Ratchet Wrenches, of which the following is a specification.

My invention relates to wrenches, one of its objects being to provide a very simple and highly efficient wrench that may be effectively used in very close or tight places where wrenches of the usual type cannot be used. The scope of my invention extends to whatever construction may be defined by or included within the terms or language of the appended claims.

In the drawings:

Figure 1 is a view in perspective of my improved wrench;

Fig. 2 is a side elevation illustrating the head portion;

Fig. 3 is a central longitudinal section thereof;

Fig. 4 is a section on the line 4—4 of Fig. 3;

Fig. 5 is an elevation of a portion of the handle;

Figs. 6 and 7 are sectional views on the lines 6—6 and 7—7 of Fig. 3;

Fig. 8 is a view in perspective partially broken away of a portion of the handle;

Fig. 9 is a view in perspective of the pawl;

Fig. 10 is a plan view of another embodiment of my invention partly broken away;

Fig. 11 is a central longitudinal section therethrough; and

Fig. 12 is a detail view of the pawl.

My invention in the form or embodiment shown in the drawings, and briefly described,

comprises a head portion 10, which, for simplicity of construction and assembly, I constructed in two halves which may be held together by means of screws 11, or in any

other suitable manner. From the body portion 10, is extended a cylindrical portion 12, which is integral with the body portion for the purpose of supporting the tubular handle 13.

The bevel gear 14, is provided with upper and lower shaft portions or trunnions 15, and 16, which are journaled in suitable bearings provided by the head portion 10. For the purpose of adapting my improved wrench for various sized bolts or nuts, I

provide the end of the shaft 16, with polygonal faces so that various sized extensions 17, may be readily inserted thereon.

Adjacent to the upper end of the bevel gear 14, is secured in any suitable manner, 60 a toothed disk or ratchet wheel 18, for a purpose to be hereinafter described. A bevel pinion 19, is adapted to mesh with the bevel gear 14, and has secured thereon an operating shaft 20, and is extended centrally through the handle 13. The extreme end of the operating shaft 20, is provided with flattened faces so that an operating handle 21, may be readily placed thereon when it is desired, to quickly rotate the 70 gear 14. The operating shaft 20, is journaled in a bearing 22, in the body portion 10, at the outer extremity of the handle 13, within a bushing or collar 23.

Pivotedly mounted within the body portion 10, by means of a suitable shaft or trunnion 24, is a double tooth pawl 25, which may be either entirely disengaged from the ratchet wheel 18, or by causing one or the other of the teeth to engage with the ratchet wheel, it will be readily seen that said ratchet wheel will be caused to rotate in either one direction or the other. On the side of the pawl 25, opposite that of the trunnion 24, is an integrally formed lug 26, 85 for the purpose of receiving one end of the relatively thin spring wire 27. This spring wire 27, extends through the tubular handle 13, approximately midway between the handle and the operating rod 20. 90

A comparatively thin sleeve 28, is freely mounted to oscillate within the tubular handle 13, and is provided adjacent to the inner end with the outwardly extending apertured lug 29, through which is passed 95 the spring wire 27.

Adjacent to the outer end of the tubular extension 12, I provide a nurled collar 30, which is mounted to freely oscillate on the tubular handle 13. For the purpose of 100 oscillating the sleeve 28, by means of the nurled collar 30, I provide a rivet or pin 31, which is securely fastened to both the sleeve 28, and the collar 30.

An apertured lug 32, somewhat similar 105 to the lug 29, is secured on the inner side of the tubular handle 13, for the purpose of receiving the outer extremity of the spring wire 27. A suitable rivet is secured to the inner side of the handle 13, imme- 110

diately opposite the lug 32, for the purpose of supporting the outer ends of the coil spring 33.

As clearly illustrated in Figs. 5, 7 and 8, I provide a transverse slot 34, in the tubular handle 13, and inwardly extending depressions or enlarged cut-out portions 35, which communicate with the slot 34, for the purpose of receiving and locking the pin or rivet 31. The depressions or recesses 35 are so predeterminedly spaced so as to cause the pawl 25, to be set in any one of the three positions already described. This, of course, accomplished by means of the flexible wire 25, being supported at one end by means of the stationary lug 32, and caused to bend by means of the movable lug 29, which is actuated by means of the nurled collar 30, through the medium of the pin 31, as is clearly shown in Fig. 4, of the accompanying drawings.

To prevent the pin 31, from being accidentally displaced from any one of the several depressions 35, I provide one end of the sleeve 28, with a flange 28', which not only serves as a strengthening or reinforcing means for the relatively thin tubular sleeve 28, but it forms a ledge against which the coil spring 33, effectively bears.

With special reference to Figs. 3 and 4, it would be readily understood that one end of the spring wire 27, being located in the fixed lug 32, and the opposite end being secured to the lug 26, of the pawl that the deflection of the spring wire 27, which is caused by the rotation of the tubular sleeve 28, will effectively oscillate the pawl 25, to either of the extreme positions.

As illustrated in Figs. 10 and 11, I often found it advantageous to tilt the handle 13, at an angle of approximately 30 degrees, this being very useful in particular classes of work. In these figures, also, I have also illustrated a somewhat different and novel construction of pawl 40, which is provided with upper and lower trunnions 41 and 42, and rearwardly extending projections 43, which is provided with a somewhat reduced end 44.

Instead of permitting the spring wire 27, to directly connect with the pawl 40, I interpose a tightly wound coil spring 45, between the inner end of the wire 27, and the reduced portion 44. This arrangement permits of a very easily operated pawl and rivet mechanism.

It will be thus readily seen then that a wrench constructed in either of the embodiments illustrated and described provides a tool that may be readily operated by means of the handle 21, in which case the tubular handle 13, would be stationary or it may be operated by turning the entire wrench bodily in either one direction or the other as for tightening or loosening various sized bolts or nuts.

It is to be understood that various forms or modifications may be resorted to without departing from the spirit or scope of the accompanying claims.

I claim:

1. A wrench comprising a hollow head portion, a tubular handle carried thereby, a rotably mounted ratchet wheel, a pivotally mounted pawl, a flexible wire carried by the pawl, a sleeve loosely mounted to oscillate within said tubular handle and having an apertured lug for the reception of said wire, and means connected to said tubular sleeve for actuating said pawl.

2. A wrench comprising a hollow head portion, a tubular handle carried thereby, a ratchet wheel, a pivotally mounted pawl, a flexible wire carried by the pawl and located within said tubular handle, and means for causing the deflection of said flexible wire for oscillating the pawl to predetermined positions.

3. A wrench of the character described, comprising a ratchet wheel, a tubular handle provided with a transverse slot therein, said tubular handle having a plurality of enlarged cutout portions equidistantly spaced about the periphery thereof, a pin secured to said tubular sleeve and extending outwardly through said transverse slots, a spring for normally retaining said pin in one of the respective cutout portions, a pivotally mounted pawl, and flexible means interposed between said pawl and the tubular handle for actuating said pawl.

4. In combination with a wrench, a pawl and ratchet, and a tubular handle, a loosely mounted tubular sleeve having an apertured lug secured thereto and loosely mounted within the handle, flexible means interposed between said pawl and the tubular handle, and operating means located on the outer surface of the handle and connected to said tubular sleeve for actuating the pawl.

5. A wrench of the character described, comprising a tubular head portion having a lateral extension integral therewith, a tubular handle carried by the extension and provided with a transverse slot having a plurality of enlarged cutout portions extending partially about the periphery thereof, a nurled collar mounted to oscillate on the outer surface of said tubular handle, a tubular sleeve loosely mounted on the inner side of the tubular handle, a pin connected between said nurled collar and the tubular sleeve, a ratchet wheel, a pawl pivotally mounted adjacent to the ratchet wheel, and flexible means interposed between said pawl and the tubular handle for actuating the pawl.

In testimony whereof I hereunto affix my signature.

FREDERICK WATERS.
